UNITED STATES PATENT OFFICE

108,726

DESIGN FOR A PIECE OF CONFECTIONERY

William S. Brodes, New Haven, Conn.

Application September 23, 1937, Serial No. 71,762

Term of patent 7 years

To all whom it may concern:

Be it known that I, William S. Brodes, a citizen of the United States residing at 384 Sherman Avenue, in the city of New Haven, county of New Haven, State of Connecticut, have invented a new, original, and ornamental Design for a Piece of Confectionery, of which the following is a specification, reference being had to the accompanying drawing, forming part thereof.

Figures 1, 2 and 3 are respectively a plan view, an elevation, and a sectional view of a piece of confectionery, showing my new design.

I claim:

The ornamental design for a piece of confectionery, as shown.

WILLIAM S. BRODES.
